UNITED STATES PATENT OFFICE.

E. P. FOWLER, OF BROOKLYN, AND C. J. CLEMENTS, OF MOTT HAVEN, N. Y.

IMPROVEMENT IN DOOR-LOCKS.

Specification forming part of Letters Patent No. 91,733, dated June 22, 1869.

To all whom it may concern:

Be it known that we, EDWIN P. FOWLER, of Brooklyn, in the county of Kings and State of New York, and CHARLES J. CLEMENTS, of Mott Haven, in the county of Westchester and State of New York, have invented, made, and applied to use a certain new and useful Improvement in Locks; and we do hereby declare the following to be a full, clear, and exact description of the said invention, reference being had to the annexed drawing, making part of this specification, wherein—

Figure 1 is an elevation of our lock with the cap-plate removed, the bolt being withdrawn. Fig. 2 is a similar elevation with the bolt projected. Fig. 3 is a cross-section of the tumbler-box at the line x x , and Fig. 4 is a longitudinal section of the tumbler-box and guard-plate.

Similar marks of reference denote the same parts.

Latches have heretofore been made in which a plate-key is used to operate upon tumblers; but in locks of this character the key could only be entered from one side of the lock, and hence was not adapted to hotel-doors, night-latches, and places where the key could be used to advantage on either side of the door.

The nature of our said invention consists in a swinging box containing tumblers that can be acted upon by a key introduced on either side of the lock; and we combine therewith a guard-plate, that is fitted so as to prevent the lock being locked, except by the proper key, as well as preventing the unlocking, except by the key. Thereby there is no opportunity to determine the position that the tumblers have to be placed in for opening the lock, and preventing any impression of the tumblers being taken when the bolt is drawn back.

In the drawing, a represents the box of the lock; b , the cap-plate; c , the bolt; d , a check-tumbler upon a fulcrum, e , and acting with the stud 2 to keep the bolt projected or retracted. f is the box for the tumblers g , and h is an arm projecting from the side of the box f , so as to work the tumbler d and project or retract the bolt c . The box f is fitted to turn upon the hubs or disks k , that are formed with the box f , and occupy circular

openings or recesses in the box of the lock and cap-plate, and in these hubs k are the openings l for the key m . The tumblers g are upon the fulcrum-pin i , that is across the box f , and is at right angles to and intersects the axial line upon which the box f and hubs k swing, so that the key-holes l can be placed in corresponding positions in the hubs k , and the key hence will act upon opposite ends of the swinging tumblers g , giving the same extent of movement to each tumbler, whether the key is introduced at one key-hole or at the other. The ends of the tumblers that come toward the guard-plate o are provided with notches. We prefer to introduce several false notches, and in each tumbler one notch, 3 , of the requisite depth. The guard-plate o slides in grooves in the inner faces of the tumbler-box f , and is connected, by a link, p , to a stud, 4 , and this is located so that the guard-plate will be pushed in and then pulled out by the box being turned from the position shown in Fig. 1 to that shown in Fig. 2.

It will now be understood that the key-bits are so formed that the key, when pressed into place, will bring all the notches 3 in line with the guard-plate, as seen in Fig. 3, and hence the end of the guard-plate o will slide into said notches as the tumbler-box is swung; but, if the notches are not properly placed, the tumblers and end of the guard-plate, coming into contact, prevent the box f being moved, and hence the lock cannot be opened.

What we claim, and desire to secure by Letters Patent, is—

The box f , fitted to swing upon the hubs k , in combination with the tumblers g , fitted to be acted upon directly by the key at opposite sides of the fulcrum when the key is introduced from either side of the lock through either key-hole l in the respective hubs, substantially as set forth.

In witness whereof we have hereunto set our signatures this 12th day of October, A. D. 1868.

EDWIN P. FOWLER.
CHARLES J. CLEMENTS.
